Specification for Design.

Patented Dec. 14, 1915.

Application filed August 20, 1915. Serial No. 46,564. Term of patent 7 years.

To all whom it may concern:

Be it known that I, FREDERICK W. BRAY, a citizen of the United States, and a resident of Greenwich, in the county of Fairfield and State of Connecticut, have invented a new, original, and ornamental Design for a Spoon, Fork, or Similar Article, of which the following is a specification, reference being had to the accompanying drawing, forming a part hereof.

Of the drawing: Figure 1 is a plan view of the handle, the bowl of the spoon or tines of the fork being of any conventional form;

Fig. 2 is a fragmentary side elevation of a portion of the handle; Fig. 3 is a fragmentary cross section on the line 3—3 of Fig. 1; and Fig. 4 is a fragmentary cross section on the line 4—4 of Fig. 1.

I claim:

The ornamental design for a spoon, fork or simliar article as shown.

FREDERICK W. BRAY.
